UNITED STATES PATENT OFFICE.

MATTHEW A. BRANDT, OF MINNEAPOLIS, MINNESOTA, ASSIGNOR TO J. G. EDDY, OF MINNEAPOLIS, MINNESOTA.

COMBINED LETTER-SHEET AND ENVELOP.

1,340,114.

Specification of Letters Patent.

Patented May 11, 1920.

Application filed September 30, 1916. Serial No. 123,118.

To all whom it may concern:

Be it known that I, MATTHEW A. BRANDT, a citizen of the United States, residing at Minneapolis, in the county of Hennepin and 5 State of Minnesota, have invented certain new and useful Improvements in Combined Letter-Sheets and Envelops, of which the following is a specification.

The present invention relates to paper receptacles and has particular reference to new and useful improvements in combined envelops and letter sheets, an object of my invention being to produce an envelop and letter sheet combined which is simple in construction, novel, cheap to manufacture and sell and practicable and adapted for use either in social work or in business, the arrangement of the letter sheet being such that the reading matter to be applied thereto may 20 be by hand-writing, typewriter, or printing.

Another object of my invention is to provide an article of the class described, which owing to the relatively flat arrangement of the integral parts thereof may be readily inserted into a typewriter, printing machine or the like without difficulty for the addressing of the envelop and writing upon the letter sheet in a single operation, thus obviating first handling the envelop and subsequently the letter sheet, the latter forming a continuation of the sealing flap when folded for continuous writing on both the sealing flap and the letter sheet, as well as permitting the addressing of said flap and sheet 30 simultaneously in a single operation.

A further object of my invention is to provide an article of the class described which in use will save the time of the writer whether a stenographer or another, the parts 40 of the device being evenly assembled, and to prevent errors in inclosing mail in envelops, which often causes unnecessary delay and expense to the parties concerned.

Other objects and advantages to be derived from the use of my improved envelop and letter sheets combined will appear from the following detailed description and the claims, taken with an inspection of the accompanying drawings, in which:

50 Figure 1 is a plan view of the envelop blank and the letter sheet;

Fig. 2 is a perspective view of the envelop showing the letter sheet prior to folding and insertion;

55 Fig. 3 is a plan view of the envelop and

sheet after the writing operation is completed;

Fig. 4 is a perspective view showing the letter sheet about to be inserted, and

Fig. 5 is a plan view of the envelop closed 60 and in process of sealing.

Referring more particularly to the drawings, wherein similar characters of reference designate like and corresponding parts throughout the various views, 1 designates 65 the body of my improved envelop, the same being formed of a blank of paper having a closure flap 2, end flaps 3 and a body or bottom flap 4. The end flap 3 terminates short of the upper edge of the body. In building 70 up the envelop the end flaps 3 are folded inwardly upon the body 1 and the body flap 4 folded upon the end flap 3 and connected thereto by an adhesive composition such as 75 glue or the like.

The letter sheets are designated 5 and are connected to the body 1 as indicated at a by an adhesive composition, each of the sheets being perforated as at B. The perforations may be omitted if desired but may be found 80 useful when not requiring the number of sheets provided and also to facilitate removal of the sheets by the person receiving the letter. The flap 2 of my improved envelop is provided with a gummed portion 85 6 for sealing purposes.

I desire to call particular attention to the position in which the sheets 5 are arranged as well as the attachment of the same to the body of the envelop adjacent the flap 2. 90

In using my improved envelop and letter sheets the same are arranged as shown in Fig. 3 and placed within a typewriter with the outer surface of the outermost sheet 5 exposed. If it is desired to simultaneously 95 address the envelop and the letter sheet a sheet of carbon paper may be inserted beneath the flap 2 whereupon the original address will appear upon said flap and the duplicate of the same will appear on the sheet 100 next underneath the flap. Of course, the second sheet of the letter, that is, the carbon of the letter, is inserted beneath the uppermost sheet and in this manner the envelop may be addressed, the original of the letter 105 and the duplicate of the letter in a single operation.

After the reading matter has been applied to the letter sheets or sheet the same may be folded in the usual manner for insertion into 110

the envelop, whereupon the flap may be sealed for transmittal.

In connection with the objects set forth in the foregoing as well as the advantages apparent therefrom, I desire to direct attention to the fact that my invention affords a novel and practicable means for reserving a postal record of each and every item of correspondence received. This may be done by the receiver of the letter. By opening the envelop carefully the body of the same may be preserved together with the letter sheet and placed in a file in the usual manner. The sender of the letter will place the date of mailing as well as the time mailed upon the flap under the address and in this manner an accurate record may be kept of exactly when the letter was mailed and received. I also lay particular stress upon the addressing feature of my invention this greatly increasing the capacity of a given stenographer as well as making more accurate the work performed.

From the above description taken in connection with the accompanying drawings, it is thought that a clear and comprehensive understanding of the construction, operation and advantages of my invention may be had, and while I have shown and described the device as embodying a specific structure, I desire that it be understood that such changes may be made in said structure as do not depart from the spirit and scope of the invention as claimed.

Having thus fully described my invention, what I claim as new and desire to secure by Letters Patent, is:—

1. The combination with a permanently

formed envelop having a sealing flap, of a writing sheet, having one edge permanently connected to the envelop interiorly thereof on the inner face of its front portion adjacent to the line of fold of the sealing flap and free therefrom, and normally outside of said envelop for underlying the sealing flap, and adapted to be received within the envelop.

2. The combination with a permanently formed envelop having a foldable sealing flap, of a writing sheet, having one edge connected to the envelop interiorly of the same adjacent to the line of the fold of the sealing flap and free therefrom and normally without said envelop for underlying the sealing flap, and adapted to be received within the envelop, said sheet having a weakened line for the separation of the sheet contiguous to the point of connection thereof with the envelop.

3. The combination with a permanently formed envelop having a foldable sealing flap, of a writing sheet, having one edge connected to the envelop interiorly of the same adjacent to the line of the fold of the sealing flap and free therefrom and normally without said envelop for underlying the sealing flap, and adapted to be received within the envelop, said sheet having a weakened line for the separation of the sheet contiguous to the point of connection thereof with the envelop, the sealing flap being provided with adhesive substance on its surface next to the sheet and free therefrom.

In testimony whereof, I affix my signature hereto.

MATTHEW A. BRANDT.
